UNITED STATES PATENT OFFICE.

JAMES JARVIS PREBLE, OF NEWTON, MASSACHUSETTS.

TOOL OR APPARATUS FOR APPLYING COATING.

Application filed May 8, 1924. Serial No. 711,829.

This invention relates to tools or apparatus for applying coating to surfaces, the present application being a continuation as to certain common subject matter of my co-pending application Serial No. 540,568, filed March 2, 1922.

The coating, if a liquid may be a paint, japan, varnish or other suitable coating medium or, if desired, it may be a solid in powdered form. The material or surface to which the coating is to be applied may be of any character such, for example, as wood, metal, or other material.

In the accompanying drawings:

Fig. 1 is a vertical, longitudinal section taken substantially centrally through the tool or apparatus;

Fig. 2 is a horizontal, longitudinal section through the body of the tool or apparatus shown in Fig. 1;

Fig. 3 is a front elevation of the upper portion of the tool or apparatus;

Fig. 4 is a side elevation upon a smaller scale of the tool or apparatus;

Fig. 5 is a horizontal section on the line 5—5 of Fig. 4 looking in the direction of the arrows.

Referring more particularly to the drawings the tool, apparatus or appliance of my invention is adapted for use in any relation for applying coating but in practice has found particularly wide use as a so-called spray gun for applying paint to metallic, wooden or other surfaces. In the disclosed embodiment of my invention the tool, appliance, or apparatus comprises generally a body portion indicated as a whole at 1 and including a forward section 2 and a rear section 3. The tool also comprises a paint or coating container 4, a cover 5 for the latter preferably formed integrally with the body portion of the tool and herein the front section 2 thereof, and a handle portion 6 suitably secured to the tool body and herein to the rear section 3 of the latter.

The container 4 is of any suitable material, as metal or glass and is adapted to be filled to the desired extent with paint or other coating material to be supplied or drawn therefrom as hereinafter described through a pipe 7 extending through the container cover and threaded as at 8 into a suitable socket or opening in the front section 2 of the tool. Upon the upper extremity of said container 4 is directly received the body of the tool, said cover 5 being shown as having

a circular or other suitably shaped depending flange 10 to fit over the upper end of the container. Herein I have shown a suitable gasket 12 positioned intermediate the cover 5 and the container.

Said container and tool body are adapted to be secured together in any suitable manner affording ready removal of the container when desired. In the present form of my invention I have provided a turned over or otherwise reinforced portion 13 at the upper end of the container whereon are provided a plurality of preferably equally spaced, laterally projecting lugs 14, three being shown herein, see Fig. 5. Said lugs are shown as rivets or may be formed integrally with the container, if desired, and are adapted to cooperate with a suitable receiving formation upon the cover portion 5 of the tool. Herein there is provided upon the inner surface of said depending flange 10 a series of partial threads, wedge formations, or the like, 15 (see Fig. 1), forming slightly inclined tracks or grooves 16 in which the lugs 14 may be received. Each such groove terminates at its lower end in a downwardly open notch or recess 17, spaced similarly as the lugs 14 and of a dimension to receive the same.

To secure the container to the spraying tool 1 it is necessary merely to insert the container within the flange 10 of the cover portion, with the lugs 14 positioned in the respective notches 17 and then relatively to rotate slightly the container and tool in a direction to cause the lugs to ride up along the tracks or grooves 16, whereby the container is wedged up against and firmly held in secured position upon the tool. Removal of the container may subsequently be readily effected by a similar but reverse operation. The gasket 12 is prevented from dropping out of the cover when the container is detached therefrom by the tracks or grooves 16 (Fig. 1). This is a great practical convenience.

The tool or appliance of my invention is particularly intended for use where a relatively small quantity of the coating material is carried by and with the tool rather than supplied thereto from a structurally separate container in communication with the tool through flexible piping or the like. An important object of my invention is to provide an inexpensively manufactured yet thoroughly efficient tool for the purpose and

particularly where but a comparatively small quantity of coating material is required for the job or work, or where changes in material are frequent.

5 The body of the tool is desirably of metal and as shown in each of the figures it is formed integrally with the cover for the container. As best seen in Figs. 1, 2, and 3 the cover is formed transversely thereof and 10 herein substantially diametrically with a wall 24 enclosing a chamber 25 communicating at its forward end with a longitudinally extending passage 26 leading to the front extremity of the forward section 2 of the tool 15 body. Said passage 26 is in turn in communication with a jet orifice 27 formed in a nose piece 28 threaded, or otherwise, but preferably removably secured at the extremity of said forward section 2, said nose 20 piece having an inclined and generally cone-shaped outer surface. Said forward section of the tool body is threaded as indicated at 29 to receive the internally threaded cap 30 having a central orifice 31 and an inclined 25 inner surface 32, a lock nut 33, if desired, being threaded on to the body in the rear of said cap 30. Said inclined inner surface 32 of the cap cooperates with the similarly enclosed outer surface of the nose piece to provide a circular or circumferential sleeve-like 30 space of adjustable cross dimension and into which the coating material is drawn to form a layer or film surrounding the central stream of motive agent issuing at the jet orifice 27.

35 The motive agent which preferably is air under pressure, is conveyed as hereinafter described into the chamber 25 where it is discharged against the layer or film-like supply or accumulation of coating material between the nose piece 28 and the cap 30. The thickness of said layer or film of coating material may be regulated by adjusting the cap 30 longitudinally upon the forward portion of the tool body or, if desired, the supply of coating material may be shut off entirely by bringing said cap into contact with the nipple 28. Said cap is readily removable for cleaning or other purposes and if desired a plurality of interchangeable caps 40 having orifices of different diameters may be provided. Said nose-piece is also readily removable, as shown, and a number of such pieces having jet orifices of different sizes may be interchangeably employed, if desired.

45 It will be observed that the motive agent is centrally applied and the paint or coating material is supplied as an annular layer or film surrounding the air passage. The paint or like material is drawn on to or deposited 50 upon and received by the outer and inclined surface of the nose-piece 28, that is, between said surface and the inclined inner surface 32 of the cap 30. The said paint or material is supplied or drawn into the annular space described through the suction or com-

bined suction and ejector effect of the motive agent or air under pressure supplied to the passage 26. The rush of the motive agent or air induces a suction or vacuum within the interior of the cap 30 which is in communication with the supply of coating material in the container by means of one or more longitudinal passages 34, see Fig. 1, in communication with the supply pipe 7, drawing therethrough a supply of coating material 55 to be deposited between the nose-piece 28 and cap 30 for discharge together with the motive agent as a mist or cloud. With the construction described the coating material in the container is not under pressure but is drawn or supplied from the container in the manner disclosed. The air in the container above the level of the coating material is preferably maintained at atmospheric pressure as by means of the small opening 35 in 60 the cover; see Fig. 2.

Desirably I provide means for supplementally discharging the air or other motive agent onto the discharge cloud or mass of paint or coating material and the main discharged air to produce, when desired, a wider or fan-shaped spray of variable width and thickness. For this purpose I have herein represented the body portion of the tool as having a passage 36, see Fig. 1, in communication with the longitudinal passage 26 and extending substantially radially outwardly through the wall of the tool body. Mounted upon the forward portion of said tool body and to the rear of the nut 33 is a cylindrical head or sleeve 37 carrying at diametrically opposite points thereon the supplemental jet members 38, 38 extending substantially in parallelism with the main air passage. The passage 36 is in communication with a transverse passage 39 formed in the head 37, said transverse passage as shown extending completely about the tool body and being in communication, at opposite sides of the latter, with the longitudinal passages 40, 41 in the supplemental jet members respectively. Near their forward ends said passages 40, 41 are provided with inclined discharge orifices 42, 43 whereby the air is supplementally discharged upon the 100 mass or cloud of paint and the primarily discharged air to effect the spreading or flattening of the same.

The supplemental air discharge is desirably readily controllable and for this purpose I have provided a valve 44 having an inclined lower end 45 adapted to seat against the similarly formed upper end of the passage 36 so as to cut off entirely or to control the flow of air therethrough. Referring particularly to Fig. 1, said valve 44 is secured at its upper end to a valve operating member shown as a cap 46 desirably having a knurled or rough exterior surface 47, and interiorly threaded as indicated at 48 to en- 105

gage a thread upon the outer surface of a boss or extension 50 on the supplemental jet head or sleeve 37. Said boss 50 is itself interiorly threaded to receive the threaded 5 bushing 51 securing in place a suitable packing 52. The construction is such that the valve is thoroughly packed against the escape of the supplemental air but may be readily manipulated, and is at the same time of 10 rugged construction and so protected as not to be easily broken in the use of the tool.

Referring to Figs. 1 and 2, the adjacent ends of the forward and rear body sections 2 and 3 are interiorly threaded to receive the 15 interconnecting threaded nipple 53, said sections being preferably locked in proper alignment as by means of the screw 54 extended upwardly through the cover 5 and tapped into said rear body portion 3. Said nipple 20 accords communication for the air between the chamber 25 on the forward body section 2 and the elongated chamber 55 in said rear body portion.

Certain varnishes, enamels and like coating materials flow out better, resulting in a 25 better finishing, if the air or motive agent is heated. Accordingly when desired I may provide means for heating the air or other motive agent prior to its discharge from the tool, such means being optional and not an 30 essential feature of my present invention. Any suitable means may be employed for this purpose but preferably I provide an electrical resistance unit indicated diagrammatically at 56 the same being received in 35 said elongated chamber 55. Said chamber is preferably formed with an internal spiral rib 57 which surrounds with a tight fit said resistance unit so as to compel the air or 40 other motive agent which enters the rear of said chamber through the passage 58 to circulate about the resistance unit during its forward travel and thus to be effectively heated. The section 3 of the body at its rear 45 or right hand end, viewing Fig. 1, desirably is slightly enlarged and is cored internally as indicated at 59 to receive an externally threaded collar 60 which secures in place a plug 61 of suitable insulating material and 50 through which extend suitable terminals 62, 63 electrically connected at their inner ends with said resistance unit 56. Said terminals are adapted to be connected with any suitable source of electricity in a manner not 55 necessary herein more fully to describe. At such times when the heating means is not to be employed the same may be removed from the tool substantially as a unit and an imperforate plug of the same outside dimension 60 as the collar 60 employed to close the rear of the tool body, or the heater may be left in the tool and the extension chord merely disconnected.

The rear section 3 of the tool body as 65 shown is formed with an integral depending portion 64 in which is formed a horizontally extending recess 65 in communication with the passage 58 constituting the inlet for the air to the chamber 55 and also in communication with a downwardly extending 70 passage 66. At its forward or left hand end, Fig. 1, said recess 65 is of enlarged diameter and interiorly threaded as at 67 to receive a valve plug 68 the latter having threaded into its outer and recessed end a 75 valve gland 69 securing in place suitable packing 70. Extending axially through said valved plug and packing is the stem 71 of a valve 72 adapted to take against the valve seat 73 of said valve plug 68. A coil spring 74 is employed to hold the valve 72 normally 80 against its seat but yieldable to pressure brought upon a suitable manipulating member such, for example, as the trigger 75 pivoted at 76 upon the tool body. The handle of the gun is preferably slightly rearwardly inclined as shown and is comprised in part by said depending portion 64 formed integrally with the tool body section 3 and in part by the handle member 6 previously mentioned. Said handle portion 6 is formed exteriorly as a continuation of said depending portion 64 and is suitably shaped to fit the hand of the operative. Desirably said handle portion 6 is hollow so as to provide a relatively large chamber 77 having communication at its upper end with the downwardly extending passage 66 of said depending portion 64. The tool body proper and said handle portion 6 are secured together in any suitable manner, preferably by the threaded nipple 78 received in aligned recesses in the adjacent portions of said handle and portion 64, a lock screw 79 engaging both said members being provided, if 90 desired. Extending through said air passage 66 and nipple and downwardly into said chamber 77 in the handle but terminating a substantial distance above the bottom wall thereof is a tube 80.

Said chamber 77 in the handle of the tool is adapted to receive, desirably at or near its lower extremity, a hose 81 which is in communication with a suitable source of motive agent as air under pressure. Said hose 81 is coupled or otherwise secured to a nipple 82 threaded into the handle portion and from which extends upwardly an open ended tube 83. Said tube 83 is desirably of sufficient length to project beyond the lower open end of the tube 80 and is out of alignment with the latter. Said chamber 77 and associated parts constitute a trap or separator for water or moisture and oil or other liquid or foreign matter, affording means, herein self-contained within the tool or appliance, for removing and collecting the water and oil or other liquid which may be carried by the motive agent such as air under pressure. Particles of water, such as may at times col- 125 130

lect in the conductors for the motive agent as by condensation or in any other manner, upon entering the chamber 77 in the handle of the tool cannot pass directly to the tube 5 80 but will be trapped and retained within said chamber thereby preventing them from mixing with and injuring the coating material. At the lower portion of said chamber I have provided an outlet 84 normally closed 10 by a pet-cock or like member 85 which may be opened to effect the discharge of the collected water when desired. If said pet-cock is opened while the motive agent is being supplied, such water will be blown out 15 through said outlet 84.

My invention is not confined to the particular structure of water and oil separator shown as any suitable means may be employed for the purpose; in some instances 20 where the separator is not necessary, as where an external separator is employed, I may omit the same, forming the handle either as shown or otherwise, as for example, in the manner similar to that shown in my 25 said copending application.

It will be observed that the entire tool is exceedingly compact being composed of three main parts, namely the container, the handle, and the body portion, the latter as 30 shown being formed in two sections. But a single valve is required, namely, that controlling the supply of the motive agent since the coating material is drawn in the manner above described from the supply within the 35 container, said supply being under atmospheric pressure only. No separate valve is necessary to control the volume of coating discharged as by varying the degree of vacuum effectively exerted through the coating 40 conduit, since this is regulatable by adjustment of the threaded cap 30 toward or away from the nose-piece 28, both of said pieces being replaceable if desired, as for instance when handling coating materials of greater 45 or less density or more or less viscosity, by similar pieces having larger or smaller orifices.

It will also be understood that in accordance with my invention the supplemental 50 jet head and passage 36 may be omitted if no spreading means is desired. Said supplemental jet or spreader means, however, par-

ticularly cooperates with the apparatus shown since by closing the valve 44 the tool may be employed without spreading effect, 55 or such effect may be obtained to any desired extent by adjustment of said valve. Also it is not essential that the disclosed means for heating the motive agent be employed since other suitable means may be 60 used for the purpose or the motive agent may be employed without heating.

My invention is not limited to the particular illustrative embodiment thereof herein disclosed. 65

I claim:

1. A spray gun having, in combination, a body portion, a cover carried thereby provided with a circumferentially depending flange having a plurality of independent 70 inclined tracks thereon, a plurality of vertical notches in the flange communicating respectively with the tracks, a container provided with a plurality of projecting lateral lugs constructed and arranged to enter the 75 notches between the tracks by a relative vertical movement of the cover and the container and to enter the tracks from said notches by a relative rotative movement of the cover and the container. 80

2. A spray gun having, in combination, a body portion, a cover carried thereby provided with a circumferentially depending flange having a plurality of independent inclined tracks thereon, a plurality of vertical notches in the flange communicating respectively with the tracks, a container provided with a plurality of projecting lateral lugs constructed and arranged to enter the notches between the tracks by a relative vertical movement of the cover and the container and to enter the tracks from said notches by a relative rotative movement of the cover and the container, and a gasket carried by the flange, said tracks being constructed and arranged to wedge the top edge 90 of the container against the gasket and also to prevent the gasket from dropping out of the cover when the container is detached therefrom. 95

In testimony whereof, I have signed my name to this specification.

JAMES JARVIS PREBLE.
